DRAW DRAPERY LAP SUPPORT

Viola F. Swafford, Big Spring, Tex.

Application July 3, 1952, Serial No. 297,035

3 Claims. (Cl. 160—341)

1

This invention relates to draw drapery supports, and more particularly to means for supporting the top inner marginal portions of draw draperies.

A main object of the invention is to provide a novel and improved draw drapery lap supporting device for use with draw drapery supports of the type having horizontally extending tongue elements to which the upper inner portions of the drapery members are adapted to be attached, the improved lap support being simple in construction, being easy to install, and preventing "dog-earing," or breaking down of the inner top marginal portions of the drapery elements when the draperies are drawn together.

A further object of the invention is to provide an improved draw drapery lap supporting device for use on the horizontally extending tongue elements of conventional draw drapery bracket structure such as shown in the U. S. patent to C. W. Kirsch 1,876,060, the improved lap supporting device being inexpensive to construct, being easy to mount on the tongue element of a drapery supporting structure, and providing a means of rigidifying the upper inner corner portions of the draw draperies to prevent collapse thereof when the draperies are drawn together.

Further objects and advantages of the invention will become apparent from the following description and claims, and from the accompanying drawings, wherein:

Figure 1 is a fragmentary front elevational view of portions of a conventional draw drapery supporting assembly of the type shown in the Kirsch Patent, 1,581,806 and the Kirsch Patent 1,876,060, showing a pair of improved drapery lap supports according to the present invention mounted on the horizontally extending tongue elements of the draw drapery supporting assembly.

Figure 2 is a top view of the structure shown in Figure 1.

Figure 3 is a cross sectional view taken on the line 3—3 of Figure 1.

Figure 4 is a front elevational detail view of the draw drapery lap supports of Figure 1 shown with their sleeve elements in unfolded positions preparatory to mounting on the tongue members of a draw drapery supporting assembly.

Referring to the drawings, the draw drapery lap supports are designated respectively at 11, 11' and are generally similar in shape, as shown in Figure 4. The lap supports 11, 11' comprise generally T-shaped bodies of flat, substantially rigid material, such as aluminum sheet, plastic

2

sheet material or the like, and are provided with the respective head portions 12, 12' and the respective stem portions 13, 13', as shown in Figure 4. The ends of the head portion 12 are provided with the respective arms or extensions 14 and 15 extending parallel to and being coplanar with the stem 13, and the ends of the head element 12' are provided with the integral extensions 14' and 15' extending parallel to and being coplanar with the stem 13'. The stem 13 is widened to define the respective bendable marginal flanges 16 and 17 which are bendable around the dotted lines as shown in Figure 2 so that the flanges 16 and 17 define a sleeve element, 18 shown at 18 in Figure 1 which is slidably engageable on the horizontally extending tongue 19 formed on the depending web member 20 of the left drapery attaching element 21 of a conventional draw drapery supporting assembly above described. The sleeve element 18 is formed with the open ended longitudinal slot 22 adapted to receive the depending web element 20 when the sleeve element 18 is telescoped over the tongue 19 in the manner shown in Figure 1. As shown in Figure 3, the sleeve element 18 is substantially flat to closely fit on the flat tongue 19 and to support the stem 13, head 12, and arms 14 and 15 in a vertical plane substantially adjacent to the upper inner portion of the drapery supported on the assembly.

Similarly, the member 11' is formed with the bendable flange elements 16' and 17' on its stem portion 13', said flange elements being bendable to define the relatively flat sleeve element 18' engageable on the horizontally extending tongue 19' at the right side of the drapery supporting assembly, the sleeve element 18' being formed with the open ended longitudinal notch 22' adapted to receive the depending web 20' of the drapery-connecting member 21'. With the sleeve element 18' engaged on the tongue 19' in the manner shown in Figure 1, the head 12', extensions 14', and 15', and the stem 13' are supported in a vertical plane substantially adjacent to the drapery, shown at 23'.

The extensions 14, 14' and 15, 15' are provided at their ends with opposing notches 24 and 24' and are further provided with notches 25 and 25' adjacent the corners between the respective head portions 12, 12' and the extensions. Similarly, said end portions of the head elements 12 and 12' are provided with notches 26 and 26', as shown in Figure 4, diagonally opposed with respect to the notches 25, 25'. The respective stem portions 13 and 13' are formed with the

opposed notches 27 and 27', as shown in Figure 4. The lap supports may thus be secured to the respective draperies by means of loops of threads 29, engaged through the material and anchored in the respective notches in the manner shown in Figure 1, thus rigidifying the inner upper corner portions of the material and preventing said upper corner portions of the material from collapsing or becoming "dog-eared" when the draperies are drawn together into overlapping relationship at their inner marginal portions.

While a specific embodiment of an improved draw drapery lap supporting device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a draw drapery lap supporting device, a draw drapery support having a vertical web and a horizontally extending tongue carried by said web to which the upper inner portions of drapery elements are adapted to be attached, a generally T-shaped body of flat substantially rigid material having a stem portion and respective arms, extensions at the ends of said arms coplanar with and parallel to said stem portion, and respective inturned marginal flanges on said stem portion defining with said stem portion a sleeve, said sleeve being engaged on the horizontally extending tongue of said draw drapery support with said arms and extensions engaged against the upper inner portion of the drapery for securement thereto.

2. In a draw drapery lap supporting device, a draw drapery support having a vertical web and a horizontally extending tongue carried by said web to which the upper inner portions of drapery elements are adapted to be attached, a generally T-shaped body of flat substantially rigid material

having a stem portion and respective arms, extensions at the ends of said arms coplanar with and parallel to said stem portion, and respective inturned marginal flanges on said stem portion defining with said stem portion a sleeve, said sleeve being engaged on the horizontally extending tongue of said draw drapery support with said arms and extensions engaged against the upper inner portion of the drapery for securement thereto, and said arms and extensions being formed with thread-anchoring notches at their edges.

3. A draw drapery lap supporting device for use with draw drapery supports of the type having vertical webs and horizontally extending tongues carried by said webs to which the upper inner portions of drapery elements are adapted to be attached, comprising a generally T-shaped body of flat substantially rigid material having a stem portion and respective arms, flat extensions at the ends of said arms coplanar with and parallel to said stem portion, and respective inturned marginal flanges on said stem portion defining with said stem portion a sleeve adapted to be engaged on a horizontally extending tongue of a draw drapery support with said arms and extensions engaged against the upper inner portion of the drapery for securement thereto, said arms, extensions and stem portions being each formed along their edges with thread-anchoring notches, one of said flanges being formed with an open ended longitudinal slot to receive the supporting web of the tongue.
